[57] **CLAIM**

The ornamental design for a horizontal type telephone protector block, substantially as shown and described.

DESCRIPTION

FIG. 1 is a front elevational view of a horizontal type telephone protector block showing my new design;

FIG. 2 is a side elevational view thereof, the opposite side being mirror image;

FIG. 3 is a transverse sectional view thereof, as seen from the plane 3—3 in FIG. 1;

FIG. 4 is a top plan view thereof; and

FIG. 5 is a rear elevational view thereof.

The terminals and apertures are partially shown in FIGS. 1, 4 and 5 for convenience of illustration.

FIG. 1.

FIG. 2.

FIG. 3.

FIG. 4.

FIG. 5.
